UNITED STATES PATENT OFFICE.

FREDERICK L. KEPPLER, OF BERLIN, GERMANY.

TRANSPARENT-TILE STRUCTURE.

1,165,417.

Specification of Letters Patent. Patented Dec. 28, 1915.

Application filed July 12, 1911. Serial No. 638,078.

To all whom it may concern:

Be it known that I, FREDERICK L. KEPPLER, a citizen of the United States, residing at Berlin, Germany, have invented a certain 5 new and useful Improvement in Transparent-Tile Structures, of which the following is a specification.

My invention relates to translucent tile structures, and particularly to means for 10 assembling the parts and for obscuring, minimizing or concealing the opaque beams whereby the units are supported.

The invention is applicable to a large 15 variety of structures, particularly sidewalk lights.

It is illustrated in the accompanying drawings, wherein—

Figure 1 is a cross section of a sidewalk light structure; Fig. 2 a plan view of same 20 with variations; Fig. 3 a cross section through a modification.

Like parts are indicated by the same letters in each of the figures.

A, A are supporting frames forming the 25 outer parts of the permanent structure; B, B are pavement units recessed at D. Each unit is provided at E around its edge and the edge of its depending rim portion with a groove for the purpose of receiving the 30 concrete grid members F, F, which are reinforced by the rods or wires G. The pavement units are separated along their upper edges for the introduction of the concrete and are in substantial contact along their 35 lower edges, each being substantially rectangular at top and bottom. The units are separated at their upper edges sufficiently to permit the introduction of the reinforcement rods from above and such rods are wholly 40 embedded in the concrete. The units may be provided with the lens formation J, J or ornamental figure work K on the upper surfaces. The reflecting surfaces N and O of the units are curved and these curves are set 45 at an angle to each other and they outwardly converge as indicated.

At the lower edges the units are provided with the curved surfaces Q, Q. Each unit thus has a rim projecting around its lower 50 portion and thus the grid members are enclosed by curved outwardly converging surfaces. I speak of these surfaces as curved, meaning, of course, thereby to include any considerable number of faces set to give the 55 general outline of a curve.

In the detail shown in Fig. 3, R is an

overlapping translucent material formed on one of the units and lapping on the joint between them. This makes an inclosing convex surface below the rim as alternative to 60 the inclosing concave surface formed by the curved surfaces Q, Q. The corrugations S, S on the curved reflecting faces form the subject matter of another application.

T is a plate which may be used to close 65 the recess in the unit so as to form a hollow unit.

U, U is an elastic or cushion portion which may be interposed between the units.

The translucent units are substantially in 70 contact at their lower margins. In practice when they are assembled, it is quite common to introduce a thin sheet of paper or the like and subsequently this is, of course, removed or brushed out, but they are still in sub- 75 stantial contact in the meaning of that expression as I have used it.

The use, operation and importance of my invention are as follows: The difficulty with 80 many such structures is that they are arranged so that their parts must be assembled and shipped, delivered and put in place as a whole or as a unit. One object of my invention is to provide means whereby the several parts may be conveniently assembled on the 85 job and in the opening they are intended to close. In most of such structures the opaque concrete is not sufficiently protected and there are frequent places where the portion of the translucent unit interposed between 90 the grid and the eye is such as to permit the eye to see the surfaces of the grid through the translucent unit. Another object of my invention is, therefore, to prevent this or greatly minimize it so that practically all 95 the light is reflected at every point where the eye is likely to look toward the grid, with the result that the grid is invisible except as to vague and shadowy suggestions of its outline.

I claim:

1. A structure consisting of a series of 105 assembled translucent units substantially in contact about their lower margins and separated about their upper margins with opposed oppositely depressed edges, each unit provided with rims outwardly projecting from one side and each bounded by converging surfaces in combination with a grid consisting of concrete filling the space between the unit edges and reinforcing bars 110 embedded in the concrete.

2. A structure consisting of a series of assembled translucent units substantially in contact about their lower margins and separated about their upper margins with opposed oppositely depressed edges, each unit provided with rims outwardly projecting from one side and each bounded by outwardly converging surfaces in combination with a grid consisting of concrete filling the space between the unit edges and reinforcing bars embedded in the concrete.
3. A structure consisting of a series of assembled translucent units substantially in contact about their lower margins and separated about their upper margins with opposed oppositely depressed edges, each unit provided with rims outwardly projecting from one side and each bounded by converging curved surfaces in combination with a grid consisting of concrete filling the space between the unit edges and reinforcing bars embedded in the concrete.
4. A structure consisting of a series of assembled translucent units substantially in contact about their lower margins and separated about their upper margins with opposed oppositely depressed edges, each unit provided with rims outwardly projecting from one side and each bounded by outwardly converging curved surfaces in combination with a grid consisting of concrete filling the space between the unit edges and reinforcing bars embedded in the concrete.
5. A structure consisting of a series of assembled translucent units substantially in contact about their lower margins and separated about their upper margins with opposed oppositely depressed edges, each unit provided with rims outwardly projecting from one side and each bounded by converging surfaces in combination with a grid consisting of concrete filling the space between the unit edges and reinforcing bars embedded in the concrete.
6. A structure consisting of a series of assembled translucent units substantially in contact about their lower margins and separated about their upper margins with opposed oppositely depressed edges, each unit provided with rims outwardly projecting from one side and each bounded by converging surfaces in combination with a grid consisting of concrete filling the space between the unit edges and reinforcing bars embedded in the concrete.

assembled translucent units substantially in contact about their lower margins and separated about their upper margins with opposed oppositely depressed edges, each unit provided with rims outwardly projecting from one side and each bounded by outwardly converging surfaces in combination with a grid consisting of concrete filling the space between the unit edges and reinforcing bars embedded in the concrete, said rims provided with curved surfaces at their lower ends beneath the lower edges of the concrete.

7. A structure consisting of a series of assembled translucent units substantially in contact about their lower margins and separated about their upper margins with opposed oppositely depressed edges, each unit provided with rims outwardly projecting from one side and each bounded by converging curved surfaces in combination with a grid consisting of concrete filling the space between the unit edges and reinforcing bars embedded in the concrete, said rims provided with curved surfaces at their lower ends beneath the lower edges of the concrete.

8. A structure consisting of a series of assembled translucent units substantially in contact about their lower margins and separated about their upper margins with opposed oppositely depressed edges, each unit provided with rims outwardly projecting from one side and each bounded by outwardly converging curved surfaces in combination with a grid consisting of concrete filling the space between the unit edges and reinforcing bars embedded in the concrete, said rims provided with curved surfaces at their lower ends beneath the lower edges of the concrete.
